(57) **CLAIM**

The ornamental design for a car adapter, as shown and described.

DESCRIPTION

FIG. 1 is a perspective view of a car adapter showing my new design;

FIG. 2 is a front elevation view of the car adapter;

FIG. 3 is a rear elevation view of the car adapter;

FIG. 4 is a left side elevation view of the car adapter; the right elevation view being a mirror image thereof; and,

FIG. 5 is a top plan view of the car adapter; the bottom plan being a mirror image thereof.

The broken lines shown represent unclaimed subject matter and form no part of the claimed design.
